UNITED STATES PATENT OFFICE.

HARRY INGRAM, OF BROOKLYN, NEW YORK.

CLOSURE FOR TUMBLERS, JARS, AND OTHER CONTAINERS.

Application filed March 14, 1923, Serial No. 624,879. Renewed January 6, 1928.

This invention relates to the sealing of receptacles such as tumblers, jars and the like for containing food or other products, and to receptacles and closures of the kind comprising 5 a side seal gasket engaged between a plain surfaced portion of the receptacle wall and the side walls of a cap having two interlocking sections of which one can be used as a service cover after removal of the other section 10 at the first opening of the closure.

Two section closures for tumblers and the like having one section readily torn off or otherwise removed so as to release the pressure on the gasket and leave the second section intact and easily lifted off, as heretofore constructed, presented various disadvantages, for example, some cannot be used with a plain walled tumbler or the like but rely on the presence of a rib or groove on or in the 20 tumbler mouth to effect the seal with the gasket, while others which are intended for use with plain-walled tumblers, have the sealing pressure between the gasket and the said walls applied by tensioning a flanged strip 25 around the gasket and securing together the ends of said strip while it is under tension, said strip forming the section which is discarded after opening the closure.

The present invention consists in the lower 30 section of the cap having its side wall converging downwardly with respect to the opposing wall of the receptacle and forming in conjunction with said wall and the side wall of the upper section of the cap, a wedge 35 shaped recess for the gasket which latter has its initial shape different from that of the recess and is deformed to tightly engage the walls thereof by forcing the cap home on the receptacle.

40 The invention provides a simple, safe, and reliable seal of the kind to which the invention relates, and the method of applying the seal merely consists in forcing the cap and gasket down onto the receptacle. The second section of the cap may be an integral ring or band, which is the simplest and strongest construction, but where a strip with ends joined by some form of mechanical lock is employed, it will be noted that the said ends can be 45 joined at the time of assembling the cap and while the strip is not under the tension incidental to making the seal.

50 Both of the closure sections may be made of tender material, as very thin sheet aluminum, and the lower edge of the lower section may be integrally formed with extending tabs or

finger-holds which may be used to tear said section upwardly to release the same from the upper section of the closure and from the tumbler when an occasion arises for unsealing or opening the tumbler. 60

The invention will be fully understood from the detailed description hereinafter presented, reference being had to the accompanying drawings, in which:

Fig. 1 is a side elevation, partly broken away, of a tumbler sealed with the closure of my invention, the closure being shown in central vertical section;

Fig. 2 is a side elevation, partly broken away, of the same;

Fig. 3 is an enlarged vertical section of one broken away portion of the closure and is presented to clearly illustrate the preferred form of gasket employed and the preferred 75 manner of placing the same in the closure or cap preparatory to the application of the closure or cap and gasket upon a receptacle;

Fig. 4 is a corresponding view showing, for 80 clearness of illustration, the two portions of the closure or cap as separated from each other and the gasket in the deformed condition in which it will appear after the cap has been applied upon the tumbler or the like and as the same is shown on a smaller scale 85 in Fig. 1;

Fig. 5 is a side elevation of the two sections, plus a gasket, of a modified construction of closure embodying features of my invention, the upper and lower sections being shown 90 juxtaposed ready for assembly;

Fig. 6 is an enlarged vertical section through one side portion of a tumbler and closure, the latter being in sealing position and embodying a further modification utilizing 95 features of my invention, and

Fig. 7 is a side elevation, partly broken away and partly in section, of the tumbler and closure illustrated in Fig. 6.

In the drawings, referring to Figs. 1 to 4 100 inclusive, 10 designates a tumbler of the usual kind employed for containing food products, 11 the contents thereof, and 12 the closure or cap for said tumbler.

The closure or cap is formed in two thin 105 sheet metal upper and lower parts 13, 14, the part 13 being of cap-like formation and comprising a top 15 of disk outline, a vertical skirt 16 depending from the edges of said top 15 and a horizontal flange 17 extending 110 outwardly from the lower edge of said skirt 16, and the lower part or section 14 compris-

ing a downwardly and inwardly converging annular band 18 having at its lower edge a depending vertical skirt portion 19 and at its upper edge a flange 20 which is spun upon 5 and engages the lower surface, outer vertical edge and upper surface of the flange 17 formed on the upper section 13 of the cap or closure. The lower section 14 also preferably has formed integrally with its lower 10 edge a suitable number of tear-off tabs 21, which may be utilized for unsealing the cap or closure when it is desired to remove the same from the tumbler. The upper and lower sections 13, 14 of the closure will preferably be formed of yielding tender material, as thin flexible sheet aluminum, which may be torn through, as to the lower section 14, with the use of the tabs 21. An upward pull on the tabs 21 will tear through the lower 20 section 14 of the closure, and that will sufficiently relieve the pressure of the lower portion of the enclosed gasket 22 against the tumbler, to permit the upper section 13 of the closure, with the gasket, to be lifted from 25 the tumbler.

The gasket 22 in the preferred form employed by me is a vertical band of yielding and preferably rubber-like material normally having a flat outer wall 23, a flat wall 24 at 30 its upper inner portion and a downwardly and outwardly beveled inner lower wall 25, and at its upper edge the gasket is adapted to engage the lower surface of the lower outer portion of the top of the upper closure-section 13. When the gasket is first applied to 35 the closure it will take the angular position in which said gasket is shown in Fig. 3, and at this time the beveled portion 24 of the gasket will stand in the path of the upper outer edge 40 of the tumbler or other receptacle 10; and when the cap or closure containing the gasket is pressed downwardly upon the tumbler or other receptacle 10, said gasket will be deformed outwardly and pressed into the 45 annular recess formed by the downwardly and inwardly converging band 18 and the vertical skirt 16 of the upper closure-section 13, then taking the form and position represented in Figs. 1 and 4 and, with sealing effect, engaging said band 18, said skirt 16 and the lower 50 surface of the outer edge portion of the disk 15, the inner wall of the gasket then being substantially flat and sealing against the side of the receptacle and the outer initially 55 straight wall 23 of the gasket taking the outline of the parts 18 and 16 of the closure, as shown in Figs. 1 and 4.

In utilizing my invention as disclosed in 60 Figs. 1 to 4 inclusive, I form the upper and lower closure or cap sections 13, 14 in separate parts and spin the upper edge portion of the lower section under and over the flange 17 of the upper section 13, thereby producing the grooved section or flange 20 which closely 65 holds and binds against the said flange 17.

The upper and lower sections 13, 14 are thus connected together and may be handled as a unit. Thereafter the gasket 22 is inserted within the outer annular portions of the cap or closure, as shown in Fig. 3, and the closure 70 may be applied to the tumbler 10. Preferably I loosely place the closure, containing the gasket, over the tumbler and introduce the tumbler into the vacuum chamber of a vacuum sealing apparatus of any suitable construction; thereafter the air will be exhausted from said tumbler and said chamber and then the cap will be pressed firmly down upon the tumbler or to the position shown in Fig. 1, and thereupon atmospheric air will be admitted to said chamber to complete the sealing, the result being that the cap and gasket will be transformed from the condition in which they are represented in Fig. 3 to that illustrated in Fig. 1, from which it will be 80 understood that the top of the cap or closure section 13 has been dished downwardly, by atmospheric pressure, within the upper portion of the tumbler and that thereby the outer edge portions of the cap or closure section 85 13 are drawn tightly against the gasket and against the lip of the receptacle. The application of the closure to the tumbler in the manner just described results in the gasket being deformed by the pressure against it of 90 the sides of the tumbler and the band 18 and skirt 16 of the closure into the outline represented in Fig. 4, and also in Fig. 1 in which it may be seen that the gasket throughout an extended sealing zone engages the upper side 95 portions of the tumbler.

The hermetic sealing of the receptacle 10 with the use of my invention may be performed in various ways and in many well known forms of apparatus commonly designated as vacuum sealing machines and also as jar sealing apparatus.

The flexible tear-off tabs 21 initially extend parallel with the side of the ring from which the lower section 14 of the closure is formed, 110 but in rolling or otherwise manipulating the ring into the form presented by the lower closure section 14, I turn the tear-off tabs 21 upwardly so that in the finished article said tabs will lie close against said section 14, as 115 shown in the drawings, and when it is desired to make use of one of the tear-off tabs 21, said tab is turned outwardly from the section 14 and then pulled upwardly so as to effect the tearing of the metal through 120 said section. When the section 14 has been torn through vertically it may be removed from the upper section 13, leaving the latter section free for removal from the tumbler 10. The section 13 is not injured by the tearing of the lower section 14, and hence said section 13 may be used as a temporary cover for the tumbler until the contents thereof have been consumed.

The construction shown in Fig. 5 em- 130

bodies a modification of the construction shown in Figs. 1 to 4 inclusive and comprises an upper closure section 30, a lower closure section 31, and a gasket 32. The closure section 30 corresponds exactly with the closure section 13 of Fig. 3 and both of said sections are vertically slit, as at 33, at a number of points through their skirt portions 16 and 34 respectively for the purpose of making it easier to remove said sections from the tumbler after the lower sections have been detached from the upper sections 13, 30. The section 30 is of cap formation and has along the lower edge of its skirt 34 an outwardly extending flange 35 corresponding with the flange 17 of Figs. 3 and 4. The lower section 31 instead of being in one continuous integral piece, as is the section 14 of Figs. 3 and 4, is of the same shape as said section 14, but is in the form of a strip having an interlock 36 of any of the several known kinds for securing the two ends of the strip together, with the grooved flange 37 of the section 31 engaged with the flange 35 of the section 30. The lower section 31 has downwardly converging sides 38 and below them a downwardly extending narrow skirt portion 39, these two features corresponding with the portions 18, 19 of the lower section 14 shown in Figs. 3 and 4. When the closure sections 30, 31 have been assembled and the gasket 32 introduced thereto, the closure may be applied to the tumbler in exactly the same manner that the closure in Fig. 3 is applied to the tumbler. Thereafter when it is desired to remove the closure from the tumbler, the interlock 36 will be released and the closure section 31 removed from the closure section 30, and thereupon the closure section 30 may be lifted from off the tumbler. The slots or slits 33 in the closure section 30 do not extend to the top of said section, but do extend through the lower edge thereof, and said slots or slits 33 being at the outer side of the gasket 32 become sealed by said gasket.

In Figs. 6 and 7 I show a further modification of certain parts of my invention and in this modified construction 40 denotes the upper closure section and 41 the lower closure section, the section 40 being in the shape of a disk-top and a depending skirt portion 42, corresponding substantially with the skirt 16 of the closure section 13, but not having at its lower edge a flange, being left plain. The lower section 41 has a vertical outwardly offset side 43, a downwardly and inwardly annular converging section 44, a lower vertical flange 45 extending downwardly therefrom and tear-off tabs 46. In the construction shown in Fig. 6 instead of flanging the upper edge of the lower section of the closure upon the lower edge of the upper section, as in Fig. 3, I flange the upper edge of the lower section 41, as at 47, over upon the upper outer edges 65 of the upper section 40, as shown in Fig. 6.

The skirt of the upper section 40 is preferably slit downwardly, as at 48, to facilitate the removal of the upper section 40 from the tumbler after the lower section 41 has been detached therefrom. Within the annular groove formed by the skirt of the upper section 40 and the portions 43, 44 of the lower section 41, I introduce a gasket 49 corresponding exactly with the gasket 22 shown in Fig. 3, and thereafter apply the closure to the tumbler, numbered 50 in Fig. 6, in the same manner that the closure of Figs. 1 to 4 inclusive is applied to the tumbler 10. The closure of Figs. 6 and 7 may be removed from the tumbler with the use of the tear-off tabs 46, said tabs being first turned outwardly from the closure section 41 and then pulled upwardly to effect the tearing through of said section 41 so that it may be readily removed from the upper section 40. The detachment of the section 41 from the section 40 leaves the latter free to be lifted off from the tumbler, this removal of the upper section 40 from the tumbler being facilitated by the slots 48 cut in the skirt portion of said section 40.

In the several forms of my invention shown, the closure is in two parts containing an annular chamber around its inner edges for the gasket 22 and within which the gasket is deformed and firmly pressed against the side of the tumbler by the mere application of the closure to position thereon, and in the forms of the invention shown in Figs. 1 to 4 and Figs. 6 and 7, the lower closure section may be torn through with the use of the tear-off tabs connected therewith, so as to become detached from the upper closure section and leave the latter free for ready removal from the tumbler. The construction shown in Fig. 5 does not require tear-off tabs on the lower section, because said section is in the form of a strip whose ends may be separated to permit of the detachment of the lower section 31 from the flange 35 of the upper section 30.

In the form of my invention shown in Figs. 6 and 7, the upper section 40 may be of paper, odorless transparent pyroxylin or other suitable material.

Some of the features of my invention may be modified. For illustration, the tear-off tabs projecting from the lower edge of the lower section of the closure may project from the upper edge of said section and be folded either downwardly against said lower section or upwardly against the upper section of the closure, this being a mere reversal as to the disposition of the tear-off tabs and within the spirit and scope of my invention.

The flange, bead or rib 17 also serves to stiffen or add strength to the skirt, which as before described is of relatively thin and flexible metal, so that additional strength is given to its entire circumference at and near

that point, with the result that when the cap is pressed on the container so as to force the elastic gasket against the wall thereof in effecting the seal, the gasket being compressed 5 more tightly is deformed and made to effectively fill or conform to irregularities in the wall of the container, whether formed therein or thereon by accident of manufacture or by design, and thus produce a more 10 effective seal than otherwise obtainable, while at the same time not detracting from the advantages which result from having the skirt of relatively thin metal or other suitable relatively thin flexible material.

15 What I claim as my invention and desire to secure by Letters-Patent, is:

1. In combination with a receptacle, a closure therefor including a cap portion, and sealing means for maintaining the cap portion tightly in place prior to the period of use of the receptacle contents, said sealing means having a downwardly converging skirt portion forming with the opposing wall of the receptacle a wedge shaped recess, a gasket within said recess, said gasket having its 20 initial shape different from that of the recess and deformed to tightly engage the walls thereof by forcing the closure home on the receptacle, and a tear-off tab integral with 25 said downwardly converging skirt portion and adapted to be pulled upwardly to tear said skirt portion and thus relieve the gasket of clamping pressure, the cap portion and sealing skirt being separable one from the 30 other when the sealing portion is released, the cap portion then being serviceable as a service cover.

2. In combination with a receptacle having plain side walls, a closure therefor comprising 35 a cap of larger area than the top of the receptacle, a skirt depending from said cap and terminating in a flange, an inwardly and downwardly extending tapered portion se-

cured to the flange, said tapered portion forming with the skirt a wedge-shaped recess, a gasket disposed within the recess and having its initial shape different from that of the recess whereby to form an air-tight seal against the side walls of the receptacle, and a tear-off tab integral with the downwardly extending tapered portion, the tab being reversely bent to lie closely against the outer surface of the tapered portion, and protected by the flange from accidental displacement, said tab facilitating removal of the tapered portion and gasket, and leaving the cap intact for use as a service cover.

3. A cylindrical jar closure comprising a cap, a skirt depending from the cap and terminating in an annular flange, a seamless 60 downwardly converging portion attached to the flange and forming with the skirt a wedge-shaped recess for the reception of a gasket, and a tear-off tab integral with the converging portion, the tearing action of 65 said tab being limited by the flange, thereby permitting removal of the closure from the jar and leaving a service cover.

4. A receptacle closure including a cap portion having a depending skirt of relatively thin flexible material formed with an annularly disposed outwardly projected rib or flange to impart a degree of stiffness to the skirt greater than otherwise existing to deform an elastic gasket interposed between 75 the skirt and wall of the container on depression of the cap to normal sealing position and cause the gasket to conform to irregularities in the wall of the container to produce an effective seal between the gasket and the wall of the container until the seal is broken.

Signed at New York city, in the county of New York, and State of New York, this 5th day of March, A. D. 1923.

HARRY INGRAM.
